UNITED STATES PATENT OFFICE.

JAMES STANLEY, OF NEW YORK, N. Y.

BUILDING MATERIAL.

No. 884,959.

Specification of Letters Patent. Patented April 14, 1908.

Application filed December 19, 1906, Serial No. 348,525. Renewed March 18, 1908. Serial No. 421,764.

To all whom it may concern:

Be it known that I, JAMES STANLEY, a citizen of the United States, and a resident of the city of New York, borough of Manhattan, in the county and State of New York, have invented a new and Improved Building Material, of which the following is a full, clear, and exact description.

The invention relates to masonry and its object is to provide a new and improved building material for use as a building or partition block, slab, ceiling plate, lath and the like, and arranged to combine strength with lightness and to aid in rendering the walls and ceilings of buildings in which the material is used sound proof, weather proof and fire proof.

The invention consists of novel features and parts and combinations of the same, which will be more fully described hereinafter and then pointed out in the claims.

A practical embodiment of the invention is represented in the accompanying drawings forming a part of this specification, in which similar characters of reference indicate corresponding parts in all the views.

Figure 1 is a sectional perspective view of the matrix when used as a lath; Fig. 2 is a transverse section of the same on the line 2—2 of Fig. 1; Fig. 3 is a sectional plan view of the same on the line 3—3 of Fig. 1; Fig. 4 is a side elevation of a modified form of the matrix as used in the manufacture of partition blocks or ceiling plates; Fig. 5 is a perspective view of the improvement in the form of a building or partition block, building slab or ceiling plate, part being broken out; and Fig. 6 is an enlarged sectional plan view of the same on the line 6—6 of Fig. 5.

The matrix or core A is formed of two sheets A', A² of paper or like material glued or otherwise fastened together and formed into spaced tubular portions A³ and intervening web portions A⁴, as will be readily understood by reference to the drawings. The web portions A⁴ are provided with apertures A⁵, and the apertures A⁵ of the successive web portions A⁴ are staggered, as plainly indicated in Fig. 1. The matrix thus formed can be used for reinforcing a building block, building slab, ceiling plate or the like made of concrete, plaster of paris or other plastic material capable of hardening, it being understood that in forming such an article, the matrix is embedded in the plastic material B,

as plainly illustrated in Figs. 5 and 6. Now by having the web portions A⁴ provided with apertures A⁵, it is evident that the plastic material extends through the said perforations, and hence securely unites the material on both sides of the matrix, at the same time securely locking the matrix in the material. The size of the tubular portions A³ and the thickness of the material B is in proportion; that is, the tubular portions increase in diameter with the thickness of the material.

When it is desired to use the matrix as a lath, the tubular portions A³ are provided with smaller apertures A⁶, as plainly indicated in Figs. 1 and 2, and in this case the tubular portions are reinforced by being filled with concrete, plaster of paris or other plastic material C (see Fig. 3), so that the latter enters the apertures A⁶ thus uniting the paper sheets at the tubular portions securely with each other. It is then simply nailed in position on the studding and the plaster is directly applied to the face of the matrix, and as the web portions A⁴ are provided with the apertures A⁵ it is evident that the said apertures readily receive the plaster and thus form keys for the same, to securely hold the plaster in position, insuring a very strong and durable lath.

From the foregoing it will be seen that by the use of the paper matrix or core, the building block, building slab or building board having a body of concrete, plaster of paris or other plastic material is immensely reinforced and at the same time the paper matrix renders the block, slab or board weather proof, sound proof and fire proof, as it is evident the sheets of paper can be treated to a fire proof and water proof solution previous to forming the same in the matrix as described.

Having thus described my invention, I claim as new and desire to secure by Letters Patent:

1. A paper matrix or core for building purposes comprising sheets of paper fastened together and forming spaced tubular portions having perforated walls, and a plastic filling material in the tubular portions.
2. A paper matrix or core for building purposes, comprising sheets of paper fastened together and forming spaced tubular portions having perforated walls, and intervening web portions having apertures, and a plastic material in the said tubular portions.

3. A building block, slab or board comprising a body of plastic material, a paper matrix embedded in the same and formed of sheets of paper fastened together and forming spaced tubular portions, and intervening web portions, the latter portions being perforated.
- 5

In testimony whereof I have signed my name to this specification in the presence of two subscribing witnesses.

JAMES STANLEY.
